Felix Moser INVENTOR

UNITED STATES PATENT OFFICE

FELIX MOSER, OF HOLLAND, MICHIGAN

DAMPER ACTION FOR GRAND PIANOS

Application filed August 25, 1927. Serial No. 215,415.

The object of the invention is to make a damper action at greatly reduced cost without impairing its efficiency.

This damper action has no bushed bearings except on the support rail. The usual damper lever is discarded and a spring takes its place. Its damper lifter flange is also done away with, the damper block taking its place.

10 In the drawings Fig. 1 is a sectional detail showing the damper action with the parts in normal position with the key at rest. The dotted lines show the damper action when the key is pressed down, lifting the dampers. 15 Fig. 2, is a fractional front view of 3 units in the direction of arrow A of Fig. 1. Fig. 3 is a view from above in the direction of arrow B of Fig. 1.

The key 1 normally rests upon the backrail 20 keycloth 2. Its contact with the damper is felted 3.

The spring rail 4 takes the place of the damper lever rail, resting on a base rail 5. A metal spring 6 takes the place of the usual 25 damper lever and is fastened onto the spring rail 4 by a screw. The edge of the spring rail 4 is felted, to avoid rattles. The forward end of the spring 6 is bent at about ninety degrees and is screwed to the damper block 7, 30 which is felted 8 where it comes in contact with the spring 6. The damper block 7 which takes the place of the damper lift flange, has the usual means for fastening the damper wire 9 by a screw 10. The damper wire 9 35 passes through the support rail 11 to the damper head 12, which is fastened to it.

When the key 1 is played, it will lift the damper 12 clear off the string 19 and will fall with the release of the key 1, the spring 6 40 aiding in damping the string 19.

The long pedal rod 13 extends upward through the keybed and the base rail 5, engages the lift rail 14, which is felted on both edges, raising said liftrail 14 the required 45 height, thereby raising all the dampers 12 at one time.

The lift rail 14 is secured to the spring rail 4. A felted stop rail 17 is fastened to the edge of the backbar 18 to safeguard against 50 raising the dampers too high.

I claim:

1. In a damper action for grand pianos, in combination with a piano key and a lift-rail operated by a pedal, a horizontally disposed flexible damper lever preferably of thin metal, one end of which being fastened to the edge of a rail generally known as the damper lever rail by a screw, the other or forward end of said damper lever being screwed to a block which is equipped with means to hold damper wire onto which the damperhead is fastened, said damperhead being disposed to be lifted manually by a key having contact with the damper lever directly under the damperblock, or by a lift-rail operated by a pedal, the flexibility of the damper lever causing the damper to drop with sufficient precision to damp the strings instantly.

2. In a damper action for grand pianos, in combination with a piano key and a lift-rail operated by a pedal, a horizontally disposed, flat and flexible spring, preferably of metal, one end of which is fastened to the damper-lever rail by a screw, the other end of said spring being fastened to a damperblock equipped with means to hold the damperwire onto which the damper is fastened, said spring being lifted at its forward end and directly under the damperblock by a manual piano key or by a lift-rail operated by a pedal, thus lifting the damper, the flexibility of the spring returning the damper to the strings the instant the key or the pedal respectively is released.

Holland, Michigan, Aug. 22, 1927.

FELIX MOSER.
